CLAIM

The ornamental design for a toner cartridge, as shown and described.

DESCRIPTION

FIG. 1 is a right, top, rear perspective view of a toner cartridge in accordance with our new design;

FIG. 2 is a left, bottom, front perspective view thereof;

FIG. 3 is a right, bottom perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a right side elevation view thereof; and,

FIG. 9 is a left side elevation view thereof.

The broken lines shown in the figures depict portions of the toner cartridge that form no part of the claimed design.

1 Claim, 9 Drawing Sheets(56)
